ABSTRACT

Electrical harness is manufactured by positioning connector housings in back-to-back relationship with their cavities in alignment, inserting wires through the aligned cavities, crimping terminals onto the ends of the wires, and moving the housings relatively along the wires until the terminals are lodged in the cavities. As an alternative embodiment, a removable guide means is used rather than the housing themselves.

2 Claims, 3 Drawing Figures

PATENTED NOV 6 1973

3,769,701

MANUFACTURING ELECTRICAL HARNESES

This application is a division of application Ser. No. 27,585, now U.S. Pat. No. 3,667,101, which is hereby incorporated by reference in its entirety.

In the accompanying sheet of drawing, three FIGURES of U.S. Pat. No. 3,667,101 are reproduced, the reference numerals and Figure identification numerals being the same as those of the patent.

In accordance with the general principles of the invention, a plurality of housings 4, 6, 8, and 10 are located in back-to-back relationship and held against each other by a removable clamping means 40. The housings have their cavities 16 in axial alignment and wires 26 are passed through the cavities. The insulation is then stripped from the wire ends and electrical terminals 24 are crimped onto the stripped ends as shown in FIG. 5. The clamping means 40 are then removed and the housings 4-10 are moved relatively along the wires until the terminals 24 are lodged in the cavities as shown in FIG. 1.

In accordance with an alternative embodiment, a guide means may be used rather than the housings, the guide means having openings extending therethrough at the same locations as the locations of the cavities in the housings. The guide means is removed from the hardness after the terminals have been inserted into the connector housings.

Specific details of the embodiments briefly described above as well as other aspects of the invention are set

forth in U.S. Pat. No. 3,667,101.

What is claimed is:

1. A method of manufacturing an electrical harness said harness comprising at least two connector housings, each of said housings having a plurality of contact-receiving cavities extending therethrough from its rearward face to its mating face and having contact terminals in said housings, and said harness further comprising conductors secured to said terminals and extending between said housings, said method comprising the steps of:

positioning said housings in back-to-back relationship with the mating faces of said housings facing in opposite directions and with the contact-receiving cavities in said housings in axial alignment,

inserting conductors through said cavities in said housings,

applying contact terminals to the ends of said conductors, and

moving said conductors relatively rearwardly through the mating faces of said housings until said contact terminals are positioned in said housings.

2. A method as set forth in claim 1 wherein said harness comprises at least three housings and in which two of said housings are positioned against a third housing with the contact-receiving cavities of said two housings in alignment with the cavities of said third housing.
